UNITED STATES PATENT OFFICE.

JOHN M. BARR, OF MILWAUKEE, WISCONSIN, ASSIGNOR, BY MESNE ASSIGNMENTS, TO
 LOUIS ALLIS COMPANY, OF MILWAUKEE, WISCONSIN, A CORPORATION OF WIS-
 CONSIN.
 ROTOR.

Application filed February 18, 1922, Serial No. 537,554. Renewed August 20, 1924.

To all whom it may concern:

Be it known that I, JOHN M. BARR, a citizen of the United States, residing at Milwaukee, in the county of Milwaukee and State of Wisconsin, have invented new and useful Improvements in Rotors, of which the following is a specification.

This invention relates to a rotor, such as employed upon an induction motor.

It applies particularly to a rotor which has its core provided with a winding having integral conductors and end rings.

This winding ordinarily is made from sheet metal and may be made from a single piece or several pieces or sections joined together.

Among the objects of the invention is to provide a rotor with a winding which may be readily and economically manufactured and applied, which is efficient, strong and durable, and which is firmly retained in place.

According to the way the invention has ordinarily been practiced, a flat sheet metal winding is first formed, and then this winding is formed into a cylinder.

The winding in cylindrical form may be made in various ways.

The cylindrical winding is placed upon the core in a position to have its longitudinal conductors register with the axial or longitudinal slots in the core, and then the end rings are perimetricaly contracted to bring the conductors in the slots and hold them therein.

The end rings may be joined before or after the winding in cylindrical form is applied to the core.

The perimetrical contraction of the end rings increases the tensile strength thereof.

The end rings by the tensile strength thereof hold the conductors in place.

The end rings may, of course, be contracted perimetricaly before the winding is applied to the core.

The basic invention disclosed herein is claimed in my copending application Serial No. 605,228, filed December 6, 1922.

The views of the drawings are:

Figure 1 is a plan of a blank from which the winding is made.

Fig. 2 is a plan of the blank, with the longitudinal conductors formed at an angle to the plane of the blank.

Fig. 3 is a perspective of the winding

formed into a cylinder with the ends joined together to form end rings.

Fig. 4 shows the cylindrical winding with the end rings of different diameters.

Fig. 5 is an end elevation of a rotor with the cylindrical winding of Fig. 4 applied thereto, the longitudinal conductors being disposed partially within the rotor slots.

Fig. 6 is a perspective of the rotor with the winding thereof in final position. 65

Fig. 7 is a perspective of a continuous winding having spirally arranged longitudinal conductors.

Fig. 8 is an end elevation of a rotor with the spiral longitudinal conductors entering 70 the rotor slots.

Fig. 9 is a perspective of the rotor with the winding of Fig. 8 in final position thereon.

Fig. 10 is a section through one of the end 75 rings, a portion of which is substantially inclosed by a circular magnetic ring of substantially U-shaped cross section.

Fig. 11 is a section through one of the end rings substantially inclosed by a circular 80 magnetic ring of substantially U-shaped cross section.

Fig. 12 is a top plan of apparatus for contracting the cylindrical winding onto a 85 rotor.

Fig. 13 is a side elevation, partly in section, of the apparatus shown in Fig. 12.

Fig. 14 is a vertical section through one of the radial plungers on line 14—14 of Fig. 12.

Fig. 15 is a view on line 15—15 of Fig. 90 14.

Fig. 16 is a top plan of one of the radial plungers.

Fig. 17 is an end elevation of one of the radial plungers. 95

A blank 1 of sheet copper or other suitable conducting material has the margins thereof bent to form double edges, and this may be done before or after the conductors are formed.

The blank 1 is then provided with spaced holes 3 near each folded edge, and with slits 4 joining opposite holes 3.

The sections between the slits 4 are then bent at an angle to the plane of the blank 105 thus forming longitudinal conductors 5 which join end conducting members 2 formed by the folded over edges.

The formed blank (Fig. 2) is then formed into a cylinder (Fig. 3) and the edges of the 110

end conducting members 2 brazed, welded or otherwise joined together to form continuous end rings of the winding.

5 The inside diameter of the winding within the longitudinal conductors 5 is slightly greater than the diameter of the slotted rotor core 6 to which the winding is to be applied.

10 One of the end rings 2 (Fig. 4) may be contracted so that the diameter of the winding inside the longitudinal conductors adjacent the end rings of smaller diameter is less than the diameter of the rotor core.

15 The cylindrical winding (Fig. 4) is now ready to be applied to the rotor core.

20 15 When applying the winding to the rotor core, the end of the winding having the larger diameter is placed over one end of the rotor core, and is thrust into place with the longitudinal conductors in the rotor slots and the end rings 2 spaced from the ends of the rotor core.

25 The winding is then contracted perimetrically and radially to force the conductors inwardly into final position in the slots.

30 25 This perimetric contraction may be accomplished by swaging or otherwise applying pressure radially to the end rings, whereby the end rings are contracted perimetrically to bring the conductors in the slots and hold them therein.

35 The end rings may be contracted one at a time or simultaneously by applying pressure radially thereto from without the end rings.

40 35 One form of apparatus for perimetrically contracting the end rings will be described later.

45 The winding in its final position on the rotor is shown in Fig. 6.

50 40 The contraction of the end rings shortens the perimeter and increases the cross-sectional area of the rings thus increasing the conductivity thereof.

45 The perimetric contraction of the end rings by applying pressure thereto radially not only reduces the diameter thereof but increases the thickness, hardness and tensile strength of the metal thereof.

55 50 The shortened end rings hold the conductors securely in place against radial displacement by the tensile strength thereof.

55 Figures 7 to 9 show a squirrel cage winding having spirally disposed longitudinal conductors applied to a spirally slotted rotor core by radial contraction of the winding as a whole.

60 The blank is punched and slotted and the longitudinal conductors bent at an angle to the plane of the blank in a manner similar to that previously described.

65 The winding is then formed into a cylinder as shown in Fig. 7, the ends of the end conducting members being welded or otherwise rigidly fastened together to form continuous end rings.

The diameter of the winding inside the spiral longitudinal conductors is slightly less than the external diameter of the rotor core, so that the winding may be applied to the core by thrusting the spiral longitudinal conductors into the longitudinal spiral rotor slots.

70 After the winding has been so positioned with respect to the slots of the core as shown in Fig. 8, the end rings are perimetrically contracted to bring the conductors into final position in the slots and hold them therein.

75 Fig. 9 shows the winding of Fig. 7 in its final position on the rotor core.

80 Any of the described methods of inserting the longitudinal conductors in the rotor slots may, of course, be employed when a winding having either straight or spirally disposed longitudinal conductors is to be applied to a slotted rotor core.

85 Figs. 10 and 11 show the end rings provided with inclosing magnetic rings for increasing the starting torque of an induction motor. The folded over portion 26 of each end ring 2, in Fig. 10, is substantially 90 inclosed by a circular magnetic ring 27 of substantially U-shaped cross section, while, in Fig. 11, the entire end ring 2 is substantially inclosed by a circular magnetic ring 28 of substantially U-shaped cross section. 95

100 When starting the motor, the frequency of the current in the rotor winding is substantially that of the source of current and the magnetic rings 27 and 28 inclosing the end rings increase the apparent resistance of the winding. As the speed of the rotor increases the apparent resistance decreases, for the frequency of the rotor or secondary current decreases as the slip decreases. So when the motor is operating at speed with 105 but a small amount of slip, the apparent resistance of the secondary winding is substantially equal to the ohmic resistance thereof.

110 The magnetic rings 27 and 28 stiffen the end rings of the winding so that during contraction thereof they do not bulge but remain substantially cylindrical.

115 The rings 27 and 28 may be made of material such as nickel steel alloy, which is magnetic below a certain critical temperature, but which at such temperature loses its magnetic property and becomes non-magnetic.

120 These rings made of such material are especially advantageous in increasing the efficiency of an induction motor when operating under load. Due to the relatively large amounts of currents in the end rings 2 under heavy loads, the magnetic rings 125 heat up to above the critical temperature and become non-magnetic, thereby eliminating the choking action thereof upon the currents in the end rings. Thus the effective conductivity of the end rings is increased, 130

and the induction motor operates with less slip.

The rings 27 and 28, if made of material which becomes non-magnetic at a critical temperature, may also serve to further increase the conductivity of the end rings when the inclosing rings become non-magnetic. If the inclosing rings 27 and 28 are spot welded to the end rings 2 and 26, as indicated at 29 and 30, or otherwise in good electrical contact therewith, the inclosing rings, when becoming non-magnetic due to increase in temperature to the critical value, assist rather than repel the flow of current in the end rings and actually become effective as conductors.

Figs. 12 to 17 show contracting apparatus for perimetrically contracting the end rings of the winding to bring the conductors thereof in final position in the core slots and hold them therein.

The contracting apparatus comprises inner and outer concentric rings 10 and 11 which are relatively movable axially.

The inner ring carries radially disposed plungers 12 which are moved inwardly by the outer ring whenever either ring is moved axially toward the other.

The inner ring 10, which may be considered the movable ring, is provided with radially disposed guideways 13 in which the plungers 12 are mounted.

These guideways 13 may be formed with milling radial slots in the ring 10 and covering the open side thereof by an annular plate 14 fastened to the ring 10 by screws 14' or other fastening means.

The outer or stationary ring 11 has an inclined inner periphery 15 which serves as a track on which the outer ends of the plungers 12 slide as the inner ring is forced down into the outer ring.

In order that the concentric relation between the spaced inner and outer rings may be maintained, a plurality of inwardly extending centering lugs 16 are fastened to the outer ring 11 by screws 17 or other fastening means.

The outer end of each plunger 12 is beveled so as to co-operate with the inclined track 15.

Each plunger is bifurcated from its head or inner end for more than one-half of its length, so the two parts 18 and 19 of the bifurcated inner end may yield toward each other as the plungers are forced toward the center.

The inner ends of the plungers are provided with concave surfaces so as to fit the cylindrical end rings of the windings which are to be contracted.

The outer edge of the plunger head part 18 is provided with tongues 20 and grooves 21 which are arranged to mesh with alternately disposed grooves 22 and tongues 23

provided in the outer edge of the head part 19 of the adjacent plunger.

Whenever an end ring of a winding is to be contracted, the inner ring 10 of the contracting apparatus is raised or drawn out of the outer ring 11 and the plungers 12 are moved outwardly until the end ring will fit within the encircling heads of the plungers.

The end ring is then placed in position within the encircling plunger heads, and the inner ring 10 lowered, so that the outer ends of the plungers engage the track 15.

Pressure is then exerted on the inner ring to force the same down into the outer ring. As the inner ring is forced down, the decreasing diameter of the inclined track causes the plungers to be forced inwardly to contract the end ring.

A convenient way to force the inner ring down into the outer ring of the contracting apparatus is to place the outer ring on the stationary base of a power press and to exert pressure on the inner ring by the movable plunger of the press.

Should a power press having an upper stationary piston and a movable bed plate supported by a plunger which raises the same be employed, the inner ring of the contracting apparatus would then be held stationary while the outer ring would be moved with respect thereto.

The winding described herein may, of course, be applied to other appliances than a rotor for the invention is susceptible of other embodiments and adaptations than those set forth as illustrations.

The invention claimed is:

1. The method of making a rotor, which consists in placing a cylindrical core with longitudinal slots into a cylindrical stamped metal winding having integral longitudinal conductors and end rings, and then contracting said end rings perimetrically to insert said longitudinal conductors in said slots and hold them therein against radial displacement.

2. The method of making a rotor, which consists in placing a cylindrical core with longitudinal slots into a cylindrical stamped metal winding having integral longitudinal conductors and end rings, and then perimetrically contracting one of said end rings to insert said longitudinal conductors in said slots and hold them therein against radial displacement.

3. The method of making a rotor, which consists in placing a cylindrical core with longitudinal slots in a cylindrical stamped metal winding having integral longitudinal conductors and end rings, one end ring being larger than the other and the longitudinal conductors near the smaller end ring being partially inserted in the longitudinal slots, and then perimetrically contracting

the larger end ring to entirely insert said longitudinal conductors in said slots.

4. A cylindrical winding for a rotor, having integral longitudinal conductors and end rings, the end rings being partially enclosed by rings which become non-magnetic as the temperature thereof increases to a critical point so as to increase the effective conductivity of said end rings.

10 5. A cylindrical winding for a rotor, hav-

ing integral longitudinal conductors and end rings, the end rings being partially enclosed by rings of U-shaped cross-section which become non-magnetic as the temperature thereof increases to a critical point so as to increase the effective conductivity of said end rings. 15

In witness whereof, I have hereunto subscribed my name.

JOHN M. BARR.
